CLAIM

The ornamental design for a bicycle rear fender, as shown and described.

DESCRIPTION

FIG. 1 is a top, rear, and right side perspective view of a bicycle rear fender showing our new design.

FIG. 2 is rear elevation view thereof.

FIG. 3 is a front elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a bottom, front, and right side perspective view thereof.

FIG. 9 is a top, rear, and right side perspective view thereof as installed on an exemplary bicycle for use, for example, with a bike share system.

FIG. 10 is a right side elevation view thereof as installed on an exemplary bicycle for use, for example, with a bike share system.

FIG. 11 is a front, top, and right side perspective view thereof.

FIG. 12 is a bottom, left side perspective view thereof; and, FIG. 13 is a bottom, right side perspective view thereof.

The broken lines showing the bicycle in FIGS. 9 and 10 are provided for the purposes of illustrating environmental structure; whereas all other broken lines show portions of the bicycle rear fender. The broken line showings of the aforementioned bicycle and portions of the bicycle rear fender do not form part of the claimed design.
